FIG. 1-4

FIG. 1-5

— 2 — 5

— 2 — 6

— 2 — 7

FIGURE 1 is a front elevational view of a combined portable lectern and public address system showing our new design;

FIGURE 2 is a side elevational view, the side opposite being a mirror image thereof;

FIGURE 3 is a top plan view;

FIGURE 4 is a rear elevational view;

FIGURE 5 is a side elevational view of the lectern shown in FIGURE 1 in open position, a microphone and support being shown in broken lines for purposes of illustration;

FIGURE 6 is a rear elevational view of FIGURE 5, an optional meter and time piece being depicted in broken lines for purposes of illustration;

FIGURE 7 is a top plan view of FIGURE 5;

FIGURE 8 is a plan view similar to FIGURE 7 but with the deck lids in raised position; and

FIGURE 9 is a sectional view taken on the line 9—9 of FIGURE 8.

The essential features of our design reside in the portions shown in full lines.

We claim:

The ornamental design for a combined portable lectern and public address system, as shown and described.
